TYPE JUSTIFYING MEANS

John Q. Sherman, Dayton, Ohio

Application February 5, 1931, Serial No. 513,737

15 Claims. (Cl. 101—403)

This invention relates to type setting and more particularly to means and a method for justifying lines of set type whereby the length of succeeding lines may be accurately equalized. The present type and method of justification is more especially adapted for use in conjunction with type setting machines of the key board type used for setting individual type for multigraphing or letter duplicating machines but which are also used for 10 setting book printing type and the like.

In the setting of type it is quite impossible to prejudge the exact length of lines of set matter which because of varying dimensions of different type and different lengths of words and intermediate spacing differ somewhat in length and would present a ragged and unsightly appearance upon a printed page. In hand setting of individual type it is customary to "justify" the lines by filling in additional quads or space elements 20 between words after the setting of the lines is completed to render the line "tight" by filling out and extending the line to a predetermined length.

In the present method of justification the line of set type is contracted after completion to the 25 desired dimension by squeezing the type comprising the set line more closely together instead of introducing additional quads or space elements as has heretofore been the common practice. To this end in the present embodiment of the invention, spacer means are provided intermediate succeeding type adapted to be compressed or collapsed under pressure or which may be embedded in the adjacent face of the succeeding type body to proportionally shorten the line of set matter.

The object of the invention is to facilitate the justification of lines of set type whereby the spacing between successive type may be substantially 30 equally distributed throughout the line thus avoiding the unsightly appearance of enlarged intermediate spaces.

A further object of the invention is to provide means whereby justification of lines of set type may be quickly and accurately effected.

A further object of the invention is to provide 45 an improved form of type body having integral means for effecting justification of a set line of type.

A further object of the invention is to provide an improved method of justifying lines of set 50 type by contracting or squeezing an extended line into a line of given dimension.

A further object of the invention is to provide 55 contractable spacer means intermediate individual type of a series.

A further object of the invention is to provide

means whereby a series of individual type may be laterally interlocked with each other.

With the above primary and other incidental objects in view as will more fully appear in the specification the invention consists of the 60 features of construction, the parts and combinations thereof, and the mode of operation, or their equivalents, as hereinafter described and set forth in the claims.

Referring to the accompanying drawing where- 65 in is shown the preferred but obviously not necessarily the only form of embodiment of the invention, Fig. 1 is a perspective view of an individual type body of the style commonly used for multigraphing or multi-letter printing apparatus and ordinarily set by type setting machines of the key board type. On this type body there are illustrated laterally projecting spacer means for engagement with the adjacent face of a succeeding type body. Fig. 2 is a plan view of a series of 70 such type elements of varying dimension set in a line. Fig. 3 illustrates several series of such type elements assembled in a chase. Fig. 4 is a perspective view of a compression plunger by which the series of type comprising the line are 75 squeezed. Fig. 5 is a plan view of a justifying press employing a series of plungers for simultaneously engaging and compressing an equal number of lines of set type whereby such lines will be contracted to uniform length. Fig. 6 is a 80 top plan view of two type bodies embodying a modification of the construction illustrated in Figs. 1 and 2. Fig. 7 is an enlarged detail view of the modification shown in Fig. 6. Fig. 8 is 85 another view of the modification disclosed in Fig. 6. Fig. 9 discloses a modified form of spacer. 90

Like parts are indicated by similar characters of reference throughout the several views.

Referring to the drawing, 1—1 are type bodies 95 to be assembled in lines for printing purposes. For illustrative purposes but with no intent to limit the scope of the invention, these type bodies have been illustrated as being of a conventional shape especially adapted for machine setting and such as are ordinarily employed in multigraphing 100 or multi-letter printing apparatus. It is to be understood, however, that the invention is not limited to this style or shape of type body, but may be applied to various forms of printing type.

In the embodiment of the invention illustrated 105 in Figs. 1 and 2 each of the type bodies 1 is provided upon one lateral face thereof with a series of projecting ribs or beads 2—2, which for convenience have been shown as prismatic or triangular form but which may be of any other suit- 110

able or desired shape. These projecting ribs or beads 2 form spacers between succeeding type bodies 1 when assembled in a succession or line of set type, thus slightly separating the individual type one from the other. The spacer beads or ribs 2 bear against the lateral face of the adjacent type element as is illustrated in Fig. 2. The assembled line of type would be slightly longer than the prescribed dimension. The assembly of type comprising the set line is then subjected to compression in a lineal direction whereby the spacer ribs or beads 2 are either distorted or collapsed to greater or less degree intermediate succeeding type bodies if the material of the type is comparatively soft or if of harder character the sharpened edges of the spacer beads or ribs 2 will be embedded to greater or less extent within the lateral face of the adjacent type body thus permitting the type bodies to approach one toward the other. While the degree of approach or contraction of the intermediate space between any two succeeding type elements will be exceedingly small, this contraction is however, cumulative throughout the length of the line and thus by compression the line may be contracted to a rather marked degree. The degree of contraction will of necessity be dependent upon the pressure applied to the line of set type.

In setting the type of the style illustrated they are assembled in a slotted chase 4, which may be the cylinder or the bed of the printing apparatus. To contract the lines of set type to uniform length, plungers 5 are introduced into the slots of the chase with thrust pressure against the type assembly. To facilitate the uniform justification or contraction of several lines of set type, plungers 5 are preferably carried upon a movable head 6 operated by an eccentric 7 or other actuator means. This movable head 6 is mounted upon a table or bed plate 8 having abutment rails 9 thereon within which the slotted chase 4 is positioned.

In lieu of distorting or collapsing the spacing ribs or beads 2 by compression or causing such beads or ribs to be embedded in the plain flat face of the adjacent type body, the latter may be formed with recesses or grooves to receive the spacer ribs 2 as is indicated at 11 in Figs. 6 and 7. These grooves or recesses as illustrated in the drawing are of substantially V shape but of slightly different angularity than that of the spacer ribs or beads 2. Thus the edges of the prismatic ribs or beads 2 of one type element will enter within the sockets or receiving grooves 11 of the succeeding type element but will bear upon the shoulders or edges of such receiving grooves 11. This affords an interlocking or interengaging coupling between succeeding type elements by which the types are held against lateral displacement. As pressure is applied to contract the line of assembled type, the ribs or beads are forced more deeply within the recess or groove 11 to compensate for contraction of the line under pressure. However at any point in this contractive adjustment there will be firm interlocking connection between adjacent type elements of the series.

In order that the distorted ribs or beads 2 may not project beyond the printing face of the type, and in order that they may not distort the printing face of the adjacent type element in which they may be embedded, the spacer ribs or beads 2 terminate somewhat below the plane of the printing face as shown more particularly in Fig. 1.

It is quite obvious that in lieu of integral spacer ribs or beads mounted upon the individual type body, prismatic, corrugated, or other

forms of compressible separate spacer elements may be introduced between succeeding type body, as is illustrated in Fig. 9. Such intermediate spacer 12 would be of such character as to yield under pressure to permit a gradual approach of adjacent type bodies. Whereas ordinarily type lines are "justified" by extension through additional quads or spaces introduced between words, the present method effects justification by contraction of an initially extended line. The differential spacing is uniformly distributed throughout the line whereby no space of excessive length results. Whereas ordinarily the differential spacing is effected only between words and usually between a few words, resulting in uneven and unsightly spacing. In the present instance the differential spacing is effected between type bodies uniformly throughout the entire line.

The sharp edges of the spacer ribs 2—2 afford minimum initial resistance to the squeezing contraction of the line whether the edges of the spacer ribs are thrust into the succeeding type or are collapsed or distorted therebetween. The resistance of succeeding spacers is substantially uniform and hence the yielding adjustment of the line is equally distributed. The resistance of the spacer ribs 2 between succeeding type gradually increases as the line is contracted, such increase of resistance being uniform throughout the series. In some instances the contractive adjustment is somewhat progressive, the sharpened edge of one spacer either yielding or entering the next type body until the increasing resistance due to the V shape of the spacer exceeds that of the sharpened edge of the spacer of the next type whereupon such contractive adjustment is repeated progressively throughout the line. Under other conditions the spacers of succeeding type yield to the lineal pressure simultaneously, and to substantially the same degree. While the resistance to contractive pressure increases due to the shape and bulk of the spacers such increased resistance is substantially uniform throughout the line.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect and the invention is therefore claimed in any of its forms or modifications within the legitimate and valid scope of the appended claims.

Having thus described my invention, I claim:

1. A series of printing type arranged in a line including at least two type, one of which has a laterally extending integral spacer and engageable with the adjacent type body to relatively separate the type bodies in a line of set type, the engaged body having depressions in the engaged face thereof of somewhat less dimension than the engaging spacer, into which the spacer normally projects, and into which it may be forced more

- deeply by pressure to proportionately shorten a line of set type.
2. The combination with a series of printing type arranged in a line, of intermediate spacers normally slightly separating the type one from another one of said spacers being offset with respect to a line determined by two of said spacers carried upon the same type, said line of type being compressible against the resistance of the interposed spacers to shorten in line to a predetermined dimension.
3. A series of printing type arranged successively in a set line of type, integral lateral projections on individual type of the series engaging with lateral faces of adjacent type in such line to relatively space the type one from another, one of said spacers being offset with respect to a line determined by two of said spacers carried upon the same type, the projections of one type being adapted to be embedded to greater or less extent in the engaged face of the adjacent type by pressure applied collectively to the line of type in the direction of its extent whereby the line will be proportionately shortened.
- 25 4. A series of printing type arranged successively in a set line of type, integral lateral projections on individual type of the series engaging with lateral faces of adjacent type in such line to relatively space the type one from another at least two of said spacers carried by a single type lying in a line parallel to the printing surface, the said projections being deformable and capable of yielding to greater or less degree in accordance with pressure applied collectively to the line of type in the direction of its extent whereby the line will be proportionately shortened.
5. A series of printing type arranged successively in a set line of type, integral lateral projections on individual type of the series engaging with lateral faces of adjacent type in such line to relatively space the type one from another, the engaged faces having therein receiving depressions of somewhat different contour into which the projections are forced to greater or less depth by pressure applied to the line of type in the direction of its extent to proportionately shorten the line.
6. Justifying means for lines of set type, comprising collapsible spacer bodies interposed between succeeding type bodies contained in the line of type said succeeding type bodies having misfitting recesses for receiving said spacers, said bodies being capable of being embedded to greater or less degree in adjacent recesses under pressure to shorten the line of type to the required dimension.
7. Justifying means for lines of set type including a plurality of deformable spacer means interposed between succeeding type bodies in the line, one of said spacer means being offset with respect to a line determined by two other spacer means carried upon a single type, said deformable bodies yielding to pressure applied longitudinally of the line of type to shorten the line to a required dimension.
8. A series of printing type arranged successively in a set line including, a type body and a plurality of deformable projections upon a lateral face of the body engageable with an adjacent type body in a line of type some of the projections carried by a single type being located in a line forming an acute angle with respect to the plane of the printing surface, said projections changing their shape under pressure applied to the type bodies to permit the approach of the bodies one toward the other to shorten a series of type to a predetermined dimension.
9. A series of printing type arranged successively in a set line of type including, a type body, and laterally extending spacers carried by the type body two of said spacers lying in a plane forming an acute angle with the line of type, said spacers being engageable with an adjacent type body to relatively separate the type bodies in a line of set type, said spacers being capable of being embedded to greater or less extent in the engaged face of the adjacent type body by pressure to effect a proportionate shortening of a line of set type to a required dimension.
10. The herein described method of justifying a line of set type consisting in initially separating the type in the set line by interposed spacers engaging misfitting recesses in the adjacent type, and thereafter squeezing the set line in the direction of its extent against the resistance of the interposed spacers to cause a proportionate approach of the type toward each other until the line of type is contracted to the required dimension.
11. The herein described method of justifying a line of type consisting in initially spacing the type one from another in the line by interposed spacers engaging misfitting surfaces and thereafter simultaneously reducing the intervening spaces between the succession of type comprising the line until the line is contracted to the desired dimension.
12. A series of telescopically adjustable printing type, including projections upon one lateral face of each type member and misfitting sockets in the opposite lateral face into which the projections of an adjacent type member extend, said type members being relatively adjustable to vary the extent of a set line of such type.
13. A type body including a plurality of substantially V shaped integral spacer elements thereon for yielding engagement with a succeeding type body, at least one of said elements being offset with respect to a line passing through two of the elements.
14. A series of printing type arranged successively in a set line of type, a plurality of integral lateral projections on individual type of the series engaging with lateral faces of adjacent type in such line to relatively space the type from one another, the projections of each type being wedge shaped and adapted to be embedded to a greater or less extent in the engaged face of the adjacent type by pressure applied collectively to a line of type in the direction of its extent whereby the line will be proportionately shortened, the wedge shape of the projections causing the projections to fall progressively and on the series simultaneously in response to increasing pressure as the distance between adjacent type decreases due to the progressive increasing cross section area of the spacers, the projections being arranged so as to provide contact with an adjacent type body upon laterally spaced-apart lines extending an appreciable extent and in the general direction from the face toward the bottom of the type body whereby to preclude rocking movement of one type body upon the projections of the adjacent type body.
15. A series of printing type arranged successively in a set line of type, a plurality of integral lateral projections on individual type of the series engaging with lateral faces of adjacent type in such line to relatively space the type from one another, the projections of each type being of

prismatic form and affording gradually increasing resistance to compressive shortening of the line of type whereby the reduction of the line will be substantially equally distributed throughout the length thereof, the projections being arranged so as to provide contact with an adjacent type body upon laterally spaced-apart

lines extending an appreciable extent and in the general direction from the face toward the bottom of the type body whereby to preclude rocking movement of one type body upon the projections of the adjacent type body.
